PORTABLE ANTENNA

Avery G. Richardson, Boonton, N. J., assignor to
Federal Telephone and Radio Corporation,
Newark, N. J., a corporation of Delaware

Application February 27, 1943, Serial No. 477,347

3 Claims. (Cl. 248—192)

This invention relates to portable antennae and more particularly to readily portable supports for antennae for field use.

It is often necessary to provide portable antennae which may be easily set up in the field. An example of such use is in the provision of portable direction finders for military use. When these antennae are of the Adcock type, the separate monopoles must be easily mounted in the field so that little time is lost in setting up the antenna for use. For this purpose tripod supports may be used.

It is a principal object of my invention to provide a rigid tripod support which may be easily and quickly set up in the field.

It is a further object of my invention to provide a tripod support which will permit mounting of the antenna above the ground so that coupling units may be readily connected to the lower end of the antenna.

It is a still further object of my invention to provide a tripod mounting which will form a relatively rigid support for the antenna and will provide for bracing against the effects of lateral forces such as wind.

It is a still further object of my invention to provide a simple fastening unit for securing the parts of the antenna support structure in position.

According to a feature of my invention, I provide a plurality of base rods adapted to be fastened together in the form of a closed geometric figure; a plurality of antenna support rods adapted to be fastened at the corners of the closed figure at one end and at their other ends fastened together forming an open pyramid to support the weight of the antenna structure and a second set of brace rods also adapted to be fastened at the corners of the closed figure at one end and fastened together at the other end to form a second open pyramid which will serve to brace the antenna against lateral displacement. To fasten together the base rods, the support rods and the base rods, I provide at each apex, an arrangement which will serve to fasten the various members and retain them in place against tension and/or compression stresses as the case may be. All the rods are preferably of insulating material such as wood.

A better understanding of my invention and the objects and features thereof may be had by reference to the accompanying drawings, in which:

Fig. 1 is a simplified diagrammatic showing

illustrating the disposition of an antenna support and antenna in accordance with my invention;

Fig. 2 is a front plane view of a specific structural embodiment of an antenna and support in accordance with my invention;

Fig. 3 is a fragmentary enlarged view of the antenna weight supporting portion of Fig. 2; and

Fig. 4 is an enlarged exploded view in perspective of the rod retaining means of Fig. 2.

Turning first to Fig. 1, 8 is a rod antenna adapted to be supported in the vertical by a supporting structure. This supporting structure comprises three base rods 10, 11 and 12 fastened together at 13, 14 and 15 to form a triangle. A set of antenna support rods each longer than half the length of the base rods are provided at 16, 17 and 18, these rods being fastened at one end to the apices of the triangle at 13, 14 and 15 and at their other ends fastened to antenna support plate 19. Rods 10, 11 and 12 are each preferably longer than the median line from the apex of the triangle to the center thereof, so that when in position they outline a pyramid. On the underside of support plate 19 is provided bracket 21 which may serve to mount the antenna coupling unit. Antenna 8 is supported and fastened to plate 19 which forces the rods 16, 17 and 18 to carry the weight of the antenna so that they are normally under compression. This weight, however, tends to force apart rods 10, 11 and 12 so, at the corners, these rods must be retained in position against tension.

To brace the antenna against lateral displacement and also hold it in a vertical position, I provide three antenna brace rods 20, 21 and 22 each longer than the antenna support rods and fastened at one end to apices 13, 14 and 15 and at their other ends connected together by antenna bracing means 23. Antenna bracing means 23 may comprise a plate with a centrally positioned hole through which the antenna rod 8 may be inserted. At each apex of the triangle are provided adjusting means 24, 25 and 26 which may serve to adjust the height of the antenna at any one corner to level up the structure.

A more complete understanding thereof of a particular embodiment of my invention may be had by reference to Figs. 2, 3 and 4 in which corresponding reference characters refer to corresponding elements of the system. In order to support rods 10, 11, 12, 16, 17, 18, 20, 21, and 22 at the apices of the triangular base, I provide at each corner a supporting structure designated generally at 24. This structure comprises a unitary structure including hollow arms 40 and

41 arranged in a common plane and at an angle to one another equal to the angle between the sides of the triangular base. In the case of a tripod support this angle should preferably be 60°. In each of arms 40 and 41 are provided bayonet slots 43 and 44 respectively, for detachably retaining the base rods in position against tension. At the apex of the angle formed by arms 40 and 41 is provided a third hollow arm 42. This hollow arm is preferably arranged in a plane bisecting the angle of the triangle and at a predetermined vertical angle depending on the length of antenna support rods 16, 17 and 18. A bayonet slot 45 is designed to retain the antenna support rods in position against compression as provided in each of the members 42.

A plate member 46 is bent in a substantial J form to fit over arms 40 and 41 and is fastened thereto. To this plate 46 is fixed a fourth hollow arm 47 adapted to be mounted in the same plane as arm 42 but at a greater vertical angle depending on the length of brace rods 20, 21 and 22. Arm 47 is provided with a bayonet slot 48 to retain the rods in position against tension and compression so that the structure will resist lateral displacement. A threaded rod 50 terminating in a foot member 51 is provided to adjust the height of the unit for the purpose of leveling the antenna. Once this adjustment has been made, the element may be locked in place by means of a screw member 52 mounted on a strip 49 and bearing against a vertical portion of plate 46.

The other ends of rods 16, 17 and 18 are detachably secured to antenna support 19 as can more clearly be seen in the enlarged view of Fig. 3. This antenna support means comprises a plate member 30 to which is fastened a cylindrical extension 31 provided at its upper end with a clamping member 32 for holding antenna 10 in position. Depending from plate 30 are three lugs 33, 34 and 35. At the end of each rod 16, 17 and 18 is provided a respective bifurcated portion 36, 37 and 38, which fit over lugs associated 33, 34 and 35 and is held in place by means such as pins 60, 61 and 62.

The other ends of brace rods 20, 21 and 22 are similarly fastened to antenna bracing plate 23 the details of which are omitted since they are substantially the same as those illustrated in Fig. 3. Plate 23, however, is not provided with an antenna supporting means to carry the weight of the antenna but instead merely has a centrally arranged opening 62 through which the antenna 10 may be passed.

It is clear that the structure in accordance with my invention provides a rigid antenna support in which all of the parts are readily detachable for storage. It should be understood, however, that although the tripod support is preferable, any suitable supporting means may be used and the antenna base may be in the form of a square or other rectilinear figure.

While I have described above the principles of

my invention in connection with specific apparatus, and particular modifications thereof, it is to be clearly understood that this description is made only by way of example and not as a limitation on the scope of my invention as set forth in the objects of my invention and the accompanying claims.

What is claimed is:

1. In an antenna support comprising three base rods arranged in the form of a triangle, three support rods, each longer than a median line from an apex of said triangle to the center thereof, and adapted to be fastened at one end at a corresponding apex of said triangle and fastened together at their other ends to form a pyramid-shaped antenna support, three brace rods each longer than said support rods, and adapted to be fastened at one end at a corresponding apex of said triangle and fastened together at their other ends to form a pyramid-shaped antenna brace, fastening means at each apex of said triangle for fastening said rods, comprising a unitary member having two hollow arms extending at an angle corresponding to the angle between the sides of said triangle and provided with tension resisting slots for detachably retaining said base rods in position, and a third hollow arm provided with a compression resisting bayonet slot for detachably retaining said support rods in position, and extending at a given angle to the plane defined by said two hollow arms, and having a fourth hollow arm member attached to said unitary member, provided with a bayonet slot for retaining said brace rods in position and extending at a predetermined angle greater than said given angle in the same plane as said third hollow arm.

2. An antenna support according to claim 1, in combination with adjustable support means fastened to said unitary member on the side opposite to said third and fourth arms for adjusting the level of said antenna support.

3. A fastening means for retaining in position at a common point a pair of base rods extending in a given plane at a predetermined angle, and a support rod and a brace rod extending in a common plane at respectively different angles to said given plane, comprising a unitary member having two hollow arms extending at said predetermined angle and provided with tension resisting bayonet slot for detachably retaining said base rods in position, and a third hollow arm provided with a compression resisting bayonet slot for detachably retaining said support rods in position and extending in said common plane at an angle to said given plane and having a fourth hollow arm member attached to said unitary member, provided with a bayonet slot for retaining said brace rods in position and extending in said common plane at a predetermined angle to said predetermined plane greater than said given angle.

AVERY G. RICHARDSON.
